(57) **CLAIM**

The ornamental design for an adhesive skin patch, as shown
and described.

DESCRIPTION

FIG. 1 is a front view of an adhesive skin patch according to
the design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is an enlarged cross-sectional view thereof, taken
along line 7-7 shown in FIG. 1;

FIG. 8 is an enlarged cross-sectional view thereof, taken
along line 7-7 shown in FIG. 1, the layers shown partially
lifted for ease of illustration; and,

FIG. 9 is a perspective view thereof.
